IMPULSE GENERATOR

Kurt Schlesinger, Berlin, Germany, assignor, by
mesne assignments, to Loewe Radio, Inc., a cor-
poration of New York

Application July 23, 1936, Serial No. 92,154
In Germany July 29, 1935

3 Claims. (Cl. 178—69.5)

The invention relates to methods and apparatus for generating very exact synchronisation impulses from sinusoidal and filtered control frequencies, these frequencies being equal to those of the impulses or to a multiple of them, and the duration of the impulses being capable of being adjusted to be as short as desired. The apparatus generates simultaneously two groups of impulses, viz., short line and long frame synchronisation impulses. It is ensured by special measures in accordance with the invention that there exists a mutual dependency of these two groups of impulses so that a frame signal can only initiate at once with a line signal or, in the case of certain methods, exactly in the middle between two line signals that is to say with the precision which is defined by the initiation of a line signal. In this way there is avoided the fluctuation of the lines in the image frequently found to be interfering in television.

The invention is illustrated in the accompanying drawings in which—

Fig. 1 shows the diagram of a single impulse generator,

Fig. 2 is an oscillogram, whilst

Fig. 3 shows the diagram of a complete generator arrangement for line and frame impulses.

As basic element for generating the impulses there is employed a reversal of the known relaxation generator, the discharge tube being used for charging the storage condenser, which has already been described and employed in itself in an earlier application (U. S. application No. 24,902, filed June 4, 1935). There is charged the condenser 1 in Fig. 1, when the tube 2 is ignited by a control impulse, by an anode battery 3 of approximately 50–100 volts. Its control grid has a strong negative bias 4 of approximately 40 volts, so that an ignition of the tube can only take place when there arrive by way of the line 5 positive potential peaks which raise the grid above the ignition value. A strong grid current is prevented in the known fashion (see U. S. application No. 668,940, filed May 2, 1933) by means of the current limiting resistance 6. After the ignition the tube is traversed by a powerful charging current until the storage condenser 1 has its full positive charge.

The charging itself, owing to the low inner resistance of the tube and if the condenser 1 is not too large, takes place extremely quickly, so that there may be obtained at 1 a positive impulse with steep front. The charging current is limited by a resistance 37, which is large in comparison with the inner resistance of the tube 2. The discharge of condenser 1 takes place through a resistance 10.

In the oscillogram, Fig. 2, there are shown two wavelengths of a sinusoidal control tone frequency. The grid bias of the tube is entered in the same diagram in the form of a broken line 12. The first ignition accordingly takes place at 5 the point 13. There immediately commences the charging period, which is completed upon expiry of the time $\tau = R_1 \cdot C$ (R_1 =inner resistance of the ignited tube, C =capacity of 1). Upon expiry of this period the impulse potential 14 in the upper 10 diagram in Fig. 2 has reached the value of the anode potential 3. The tube is extinguished at the point 15. If the leak resistance 10 were so small that the discharge were to take place according to the curve 16, i. e., that the same were 15 completed before arrival of the second control tone change, a new ignition would occur at the point 17. The number of impulses per second would accordingly be equal to the control frequency. If in accordance with the invention the 20 duration of the discharge $R_1 \cdot C_1$ is made considerably longer, i. e., the resistance 10 increased in size, so that the discharge occurs according to 25 16a, the second control-impulse is unable to effect ignition at 17 because the bias between grid 25 and cathode is still too negative, and the next ignition occurs at the point 18, i. e., omitting one control-impulse. In the case of a fixed time 30 constant $R_1 \cdot C_1$ according to curve 16a, Fig. 2, an impulse generation may be enforced at each 30 single control impulse by increasing the amplitude of the latter. In accordance with the invention the control impulses are made variable in intensity by means of a potentiometer 26, Fig. 1 (see also the bottom of Fig. 3), so that at this 35 potentiometer the sequence of impulses may be adjusted as $1: \frac{1}{2}: \frac{1}{3}$, etc.

To the discharge circuit 9, 10 an amplifying tube 19 is coupled by way of condenser 20, a grid leak resistance 21 and a grid current limiting resistance 22. This protective resistance ensures that too high positive potentials of the grid of 40 19 are avoided. It should amount to $\frac{1}{10}$ to 1 megohm being large in relation to the leak 10. By reason of its use there are obtained impulses 45 having a rectangular top.

In a television receiver two connection systems of this kind are provided. The line-impulse connection operates with $1=300$ cm., $10=.3$ megohm, whilst the frame-change connection operates with $1=30,000$ cm., $10=.1$ megohm. The two impulse generators are designated diagrammatically in Fig. 3 by T_x (line) and T_y (frame) in respect of the horizontal and the vertical axis of the image. They each act via grid current 55

limitters 22x and 22y on an appertaining amplifying tube 19x and 19y. The two anodes are connected via a common anode resistance 23 to a variable anode potential source 24 so that the impulse amplitudes of both groups are equal and adjustable. In order to avoid any reaction between amplifiers and generators there are employed as power amplifiers 19 screening grid tubes, preferably pentodes. For each screening grid and the appertaining generator a separate apparatus Nx and Ny is provided.

Now it will be described how the y-side of the arrangement (frame signal transmitter) is impelled by the mains 25 and controlled by the higher frequency (line-frequency or the double of it) produced by a separate generator synchronously driven by the same mains so that finally the mains or the frame frequency appears as an integer multiple of the higher frequency.

According to Fig. 3 the voltage of the mains 25 is reduced by way of potentiometer 26 and transformer 27 to approximately 40 volts and is adjusted in phase by a phase shifter consisting of a resistance 28 (0 to 0.1 megohm variable) and a condenser 29 (1 mf.). At the potentiometer 26 there are adjusted the number of frame changes per image according to the remarks made in conjunction with Fig. 2. The mains frequency is now first freed by means of a filter chain 30/31 of all harmonic vibrations (0.1 megohm, 0.1 mf.). The control frequency generator 45 is represented in practice by an amplifier, which is connected with a photo-cell arranged behind a rim of slots in the scanning disc 32 chopping the light of the lamp 43. The disc 32 is driven by a mains-fed synchronous motor (not shown).

It is possible by using a highly selective amplifier having a plurality of tuned circuits to obtain a very precise control frequency which is independent of irregularities of the slot divisioning in the disc 32. This signal may be equal to the frequency or to the octave of this frequency, in the latter case the apparatus Tx having the task of halving the frequency. By means of a by-pass consisting of the condenser 33 (approximately .001 mf.), the resistance 34 (approximately 0.1 megohm) an adjustable fraction of this control energy may be applied, in addition to the mains frequency, to the grid of Ty in order to secure synchronisation.

In the interlaced line-group system the octave of the line frequency is supplied by 45. In this case the octave of the line frequency, and not the line frequency itself, is likewise employed for synchronisation by way of the passage 33/34. The line frequency itself is produced only in Tx and

must be carefully withheld from the by-pass. For this purpose the series resistance 36 is provided. The operation of Ty by both frequencies has the desired effect of fixing the impulse initiation for the frame-change signals once at the commencement of the line and again at the middle of the line, as necessary in the case of the interlaced line method.

It may be specifically pointed out that in the above there have been described merely particular forms of embodiment of the general idea according to the invention, and that the stated measures may be employed and claimed both in combination as well as singly.

I claim:

1. In a television transmitter a line frequency impulse oscillation generator, a frame frequency impulse oscillation generator, an arrangement for producing a control frequency controlling the first mentioned generator, the second mentioned generator being controlled by the mains frequency, means to conduct the output of said first mentioned generator and the output of said second mentioned generator to a common point of the transmitter, said means comprising screen grid tubes connecting the output of each generator to said point and having a common anode resistance, a common anode voltage source, but separate screening grid voltage sources.

2. In a television transmitter comprising a light-chopper driven by a synchronous motor fed by the mains, a photo-cell actuated by said light-chopper and producing a control frequency equal to the line frequency, a tuned amplifier for said control frequency, a line frequency impulse generator controlled by said control frequency and an image frequency impulse generator controlled by the mains frequency and oscillating at half the mains frequency, means to conduct the said control frequency additionally to the input of said image frequency generator so as to synchronize it.

3. In a television transmitter comprising a light-chopper driven by a synchronous motor fed by the mains, a photo-cell actuated by said light-chopper and producing a control frequency equal to the double of the line frequency, a tuned amplifier for said control frequency, a line frequency impulse generator controlled by said control frequency and a frame frequency impulse generator controlled by the mains frequency and oscillating at the mains frequency, means to conduct the said control frequency additionally to the input of said frame frequency generator so as to synchronize it.
